UNITED STATES PATENT OFFICE.

MARTIAL REDON, OF LIMOGES, FRANCE.

DESIGN FOR A CUP.

SPECIFICATION forming part of Design No. 23,281, dated May 22, 1894.

Application filed September 20, 1893. Serial No. 486,036. Term of patent 7 years.

to all whom it may concern:
Be it known that I, MARTIAL REDON, a citizen of France, residing at Limoges, in the Republic of France, have invented and produced a new and original Design for a Cup, of which the following is a specification.

The accompanying drawing is a perspective view of a cup embodying my design.

The essential features of my design are lodged in an arabesque ornamentation C which is located a little below the lip of the cup, consisting of a series of curved lines terminating in a leaf-shaped ornamentation at both ends, the said leaf-shaped and curved line extending laterally but not continuously around the exterior of the cup, and between each of these curved and leaf-shaped ornamentations is a vertically arranged bead-shaped ornament. These bead-shaped ornamentations are more pronounced and larger at the top or point nearest to the lip of the cup and they gradually become less accentuated until they finally merge into the plain exterior surface

of the cup. On either side of the bead ornament, between it and the leaf shape of the curved ornament is lodged a zig-zag ornamentation. This ornamentation is more pronounced at the point nearest the lip of the cup and gradually merges into the plain exterior surface of the cup. On the handle of the cup is formed a composite arabesque and bead-shaped ornamentation.

In the drawing A is the lip of the cup.

B is the handle.

C is the curved and leaf-shaped ornamentation.

D is the zig-zag ornamentation, and E is the bead-shaped ornamentation.

What I claim is—

The design for a cup as herein shown and described.

MARTIAL REDON.
